UNITED STATES PATENT OFFICE.

JAMES CALKINS AND PHILIP A. HOVER, OF HUDSON, AND CHARLES W. GRANNIS, OF GOWANDA, NEW YORK.

IMPROVED FURNACE FOR THE COMBUSTION OF COAL-OIL AND SIMILAR HYDROCARBON FLUIDS.

Specification forming part of Letters Patent No. 28,154, dated May 8, 1860.

To all whom it may concern:

Be it known that we, JAMES CALKINS and PHILIP A. HOVER, of the city of Hudson, in the county of Columbia, and CHARLES W. GRANNIS, of Gowanda, in the county of Erie, in the State of New York, have invented a new and useful apparatus, which we term a "Fuel-Box," for the purpose of employing petroleum, coal-oil, or other hydrocarbon fluids for producing steam; and we do hereby declare that the following is a full, clear, and exact description of the same, reference being had to the annexed drawings, and to the letters of reference marked thereon, making a part of this specification, in which—

Figure 1 is a perspective view of the fuel-box and chamber-pan combined; Fig. 2, a vertical transverse section of fuel-box and chamber-pan, exhibiting the air-chamber formed between the two; Fig. 3, bird's-eye view of the fuel-pan resting in the chamber-pan; Fig. 4, bird's-eye or top view of the chamber pan detached from the fuel-pan.

The same letters indicate like parts on the several figures.

Letter A is the air-pipe which conducts air to the chamber beneath the fuel-pan. (See Fig. 2.)

Letter C is the air-chamber. (See Fig. 2.)

Letters c c c, &c., indicate the convexities formed in the bottom of the fuel-pan. (See Figs. 1, 2, and 3.)

Letters p p p, &c., are the air pipes or tubes communicating with the air-chamber, and which conduct the air into the flames of the burning fluid used for fuel.

Letter s is the supply-pipe passing through the air-chamber and communicating with the fuel-pan through the bottom at v.

Letter v is a valve which opens and closes this communication and regulates the supply of fuel as required.

The nature of our invention consists in placing beneath or connecting with steam-boilers shallow metallic vessels or pans for containing petroleum, coal-oil, or other hydrocarbon fluids to be used as a fuel, and of so constructing and arranging them that currents of air may be forced into and made to commingle with the flames of the burning fluid.

To enable those skilled in the art to make

and use our invention, we will proceed to describe its construction and operation.

As above mentioned, we place beneath or otherwise connect with steam-boilers one or more shallow metallic pans, which are supported by broad flanged margins resting on the flanged margin of another similar, but larger and deeper, vessel or pan beneath. (See these two pans as illustrated by Figs. 1, 2, 3, and 4 of our drawings.) The lower pan or vessel, Fig. 4, is so much larger than the upper or fuel pan, Figs. 1, 2, and 3, that a reservoir or air-chamber is formed between the two and space sufficient for all expansion of the upper vessel. Through the bottom of the fuel-pan (see Figs. 1 and 2) are inserted vertical tubes or pipes, which communicate with the air-chamber C beneath, and which extend so far above the fluid in the pan that no expansion or ebullition of the same will overflow their tops. These tubes or pipes p p p (see Figs. 1, 2, and 3) admit currents of air from the chamber C beneath, which mingle with the flames of the burning fluid above. The air may be admitted from above, beneath, or at the sides of the flames, and similar results will be produced.

The fuel-pans are supplied by means of a pipe, s, through the bottoms and the supply of fuel regulated by cocks or valves. It may also be admitted through the sides as well as the bottom.

w is a wire connected with the valve v to open or close the aperture through which the fluid is to be supplied. The bottoms of the fuel-pans are likewise either corrugated or provided with numerous concavities c c c, Figs. 1 and 2, to retain fluid sufficient to keep up the fires without filling the pans so full as to overflow with the motions of the boiler, with which it may be connected.

To supply the air-chamber C, we employ a blower of any of the ordinary kinds used on steam-vessels. On locomotives we contemplate using natural currents of air without the intervention of a blower.

The operation of our apparatus is indicated by the description we have given of its construction and arrangement; but to make it more plain we will state that, having admitted through the valve v sufficient fluid to just cover

its bottom we ignite it. Now, it burns with a dense black smoke. The blower being convenient, it is started by hand by means of a crank, which may be slipped on and off at pleasure. This is continued for a few moments until the steam will drive it. As soon as the currents of air are made to mingle with the flames of the burning fluid, its combustion is not only wonderfully increased but all the smoke, before so dense, is completely consumed and annihilated.

By the use of our apparatus not only a new class of materials is employed as fuel for producing steam, and for other purposes, but an immense saving—great economy in ocean navigation with steam-vessels—is effected.

To fit our fuel-pans to the boilers of steam-engines now in use, the grate-bars need only

be removed and the pans fixed in their places. The ash-pan is made tight so as to serve for the air chamber or reservoir and the margins of the fuel-pans made to rest on a flange or projection attached to the sides of the furnace.

What we claim as our invention, and desire to secure by Letters Patent of the United States, is—

The fuel-pan, in combination with the chamber-pan, and both constructed and arranged substantially in the manner and for the purpose herein set forth.

JAMES CALKINS.
PHILIP A. HOVER.
CHAS. W. GRANNIS.
